UNITED STATES PATENT OFFICE

165,485

MEMORIAL STATUETTE

Carmelo Savoca, Astoria, N. Y.

Application September 20, 1948, Serial No. 148,673

Term of patent 14 years

(Cl. D29—23)

To all whom it may concern:

Be it known that I, Carmelo Savoca, a citizen of the United States, residing in Astoria, Long Island, in the county of Queens, city and State of New York, have invented a new, original and ornamental Design for a Memorial Statuette, of which the following is a specification.

With reference to the following drawings, forming a part hereof of which:

Fig. 1 is a front elevation of a memorial statuette, showing my new design.

Fig. 2 is a side elevation thereof.

The dotted lines shown in the drawing are for illustrative purposes only.

I claim:

The ornamental design for a memorial statuette, substantially as shown and described.

CARMELO SAVOCA.
